signors to the United States of America as rep-
resented by the United States Atomic Energy
Commission

Application July 17, 1945, Serial No. 605,544

1 Claim. (Cl. 204—247)

1

This invention relates to electrolytic cells for the manufacture of fluorine by the electrolysis of fused salt electrolytes comprising an alkali-metal fluoride and hydrogen fluoride. The invention is especially concerned with the provision of a more durable anode supporting structure than hitherto developed.

In the manufacture of elemental fluorine by electrolysis of acid alkali-metal fluorides serious corrosion problems are involved. These problems result from the corrosive action of constituents of the electrolyte and the generated fluorine. They are aggravated by attempts to operate cells at high production rates and consequently at high current densities.

At high production rates the removal of heat from the electrolytic cell becomes a substantial problem. Heat removal can be accelerated by providing electrodes which are wholly immersed so that the electrolyte can circulate freely around the electrodes. With such an arrangement the cooling of the electrolyte at the cell walls increases the density of the electrolyte between each electrode and the adjacent cell wall as compared with the density of the electrolyte between the two electrodes, and circulation of the electrolyte takes place on the thermo-siphon principle. The generation of gaseous electrolytic products between the electrodes further reduces the relative densities of the liquid and accelerates this circulation.

At high current densities in particular, cell parts which are in contact with the electrolyte and which are electrically anodic are relatively rapidly corroded. When steel containers are employed for holding the electrolyte, the ferric fluoride protective coating, which normally protects steel surfaces at low current densities, fails to provide adequate protection and the metal is rapidly destroyed. In order to avoid the rapid destruction of the metal parts of the cell exposed to the electrolyte, as many of these parts as possible are insulated from the anode and maintained at a potential closer to the cathode potential than to the anode potential. Cells in which a perforated metal partition or diaphragm is provided between the anode and cathode have a diaphragm potential intermediate the anode and cathode potentials and varying in accordance with the relative position of the diaphragm. Since the potential drop between liquid and anode is greater than the potential drop between liquid and cathode, a diaphragm located at a position equidistant from the two electrodes will have a potential closer to the cathode potential.

By electrically connecting the diaphragm with the container, the container may be maintained at substantially the diaphragm potential provided that the container and diaphragm are adequately insulated from the anode and cathode. While this expedient is effective for reducing corrosion of the metal container, it is obviously incapable of use for controlling corrosion of the anode support.

10 During electrolysis the nickel anode is gradually destroyed and eventual replacement is necessary. However with previous anode supports, the corrosion of the anode has not proceeded uniformly at all areas and one of the areas of major 15 weakness has been the margin along the anode support. The metals composing the anode support itself have also deteriorated rapidly at high current densities. This rapid destruction of the anode assembly by the corrosive compounds of 20 the electrolyte might be avoided to a substantial extent by extending the nickel anode above the surface of the electrolyte and locating the connection of anode to its support entirely in the gas space of the anode chamber. However, such 25 a construction would seriously interfere with the free circulation of electrolyte with consequent increased corrosion of the anode due to temperature variations. Moreover, the adverse effects of inadequate electrolyte circulation are reflected 30 in reduced efficiency of operation as well as increased corrosion. Consequently such a structure does not provide a satisfactory solution for the problem.

35 An object of the invention is to provide an electrolytic cell capable of operation for the production of fluorine at high current densities and high efficiencies with a minimum of corrosion to cell parts. A further object of the invention is to provide an anode supporting structure which 40 will resist the corrosive effect of fluorine and hydrogen fluoride and other electrolyte components and will not only outlast the anode but will not contribute to the rapid corrosion of the anode along the margins of support. Further 45 objects will become apparent from the following description of the invention.

In accordance with the present invention a nickel anode which terminates below the normal electrolyte level is supported by supporting means comprising a portion composed of a metal having an atomic number from 26 to 29, inclusive, or an alloy thereof, welded to the nickel anode by a weld, or welds, located in rear of the anode so that it is out of the zone of active electrolysis and is shielded by the anode from the highly

corrosive environment between the anode and cathode.

With the supporting structure disposed behind the anode, the anode face opposed to the cathode presents a smooth surface free from ridges or depressions which would serve to hold elemental fluorine and form pockets of corrosion.

The anode support preferably comprises a relatively massive bar of such a metal and an element or section extending above the normal electrolyte level and presenting to the electrolyte in the zone above the nickel anode a copper or cupronickel alloy surface, which is particularly resistant to the corrosive action of the environment. Preferably the nickel anode is welded substantially completely across its face to both adjacent edges of the bar. These welds may be continuous or intermittent but should attach a major proportion of the length of each bar at both edges. Continuous welds have the advantage of providing the least resistance to current between the bar and the anode. However any irregularity in rate of nickel consumption caused by voltage drop through the supporting bar can be offset by interrupting the weld bead at the location where excessive current flows, to provide a slightly higher potential difference between the anode and the support. Normally a sufficiently large supporting bar is used to avoid material voltage drop through the support so that further equalizing measures are not necessary.

In a preferred form of the invention a steel bar is located in rear of the anode in a substantially horizontal position. The bar in turn is affixed to a copper support and connector by a weld or by means of steel bolts. The bar may be disposed at the top or bottom of the nickel anode or at an intermediate position. In this construction the life of the connector bar is promoted by its location in a shielded zone and by the coherent film of ferric fluoride which forms on the metal surface and renders it relatively insensitive to the action of the corrosive agents present in the electrolyte.

Cells constructed in accordance with the teachings of the invention have been found capable of operating for many hundreds of hours without deterioration of the electrical connection or loss of rigidity of the physical support for the nickel anode. By use of these connectors it has been possible to avoid connector corrosion problems and to operate cells for the full life of the anode (several hundred thousand ampere hours in a cell with about 7½ square feet of anode area) at high anodic current densities (150-250 amperes per square foot).

The invention is illustrated by the specific embodiments shown in the accompanying drawing wherein

Figure 1 is a vertical elevation with one end cut away to show diagrammatically the interior arrangement of an electrolytic cell embodying a preferred form of the invention;

Figure 2 is a perspective view of the anode assembly of the cell shown in Figure 1;

Figures 3 and 4 are vertical elevations showing the back and end, respectively, of an alternative anode assembly embodying the invention.

With especial reference to Figure 1, the numeral 1 designates the steel container of an electrolytic cell having a heating and cooling jacket 2 and provided with an inlet 3 for electrolyte, a drain outlet 4, and gas outlets 5 and 6 for hydrogen and fluorine, respectively. A Monel barrier 7 divides the gas space above the electrolyte into

two chambers for collecting fluorine produced at the anode and hydrogen produced at the cathode, and also supports a perforated Monel partition or diaphragm 8 for inhibiting intermingling of fluorine and hydrogen. Depending from the top of the electrolytic cell and suitably insulated therefrom are duplicate copper connectors 9 and 9', which connect to the positive pole of a suitable source of electric current and connectors 10 and 10', which connect to the negative pole. Rigidly mounted on connectors 10 and 10' is a copper cathode connector bar 11. The cathode connector bar 11 extends substantially the length of the cell and carries the cathode 13 bolted by means of countersunk bolts 12 or otherwise suitably affixed to it. Since this connector presents no corrosion problem, a welded union is not necessary. Preferably a pair of bolted copper anode connector bars 14 and 14' fixed to connectors 9 and 9' are bolted by means of steel bolts 15 to an iron or steel anode-supporting bar 16. This anode-supporting bar supports pure electrodeposited nickel anode plates 17, 17' and 17'' by means of bead welds 18 and 18' extending the length of the top and bottom edges of the bar, applied using either a steel or, preferably, a nickel weld rod.

The superior corrosion resistance of copper under the conditions prevailing in the cell is responsible for the durability of connectors 9 and 9'. If a metal such as iron or nickel is employed for these connectors, it is usually desirable to provide protective sleeves of copper or Monel.

While both connectors 10 and 10' may be connected to the current source, this is normally not necessary since the resistance of the copper bar 11 is too small to materially affect the operation of the cell.

The nickel anodes of the cell illustrated in Figures 1 and 2 are composed of three separate cathodic nickel plates to secure the desired large surface area. One or more plates may be used in this manner depending upon the size of plates available and the size of anode desired.

With particular reference to Figures 3 and 4, a plate nickel anode 21 composed of a single sheet of electrodeposited nickel is welded to a pair of square supporting bars 22 and 23 by bead welds 24, 24', 25 and 25'. Cuffs or sleeves 26 and 27, composed of copper or a copper nickel alloy, may be provided when the supporting bars are composed of another metal, to prevent corrosion of the supporting bar. While this construction is not essential, copper and its alloys have been found to be more effective than iron, cobalt, or nickel in resisting the corrosive action of the agents present in the cell electrolyte so that the life of the structure can be prolonged in this manner. The sleeves may be provided to cover only the immersed section of the bar above the anode or may extend up to the top of the cell.

The bars 22 and 23 may be cylindrical rods with a side cut away to provide a flat face adjacent the anode, or they may be rectangular, hexagonal, or octagonal bar stock, which can be turned down, if desired, to provide a cylindrical form where the bar passes through the top of the cell, as shown in the drawing.

The electrolytic cell illustrated is designed for operation with an electrolyte level above the top of the anode and cathode so that electrolyte can circulate freely around the electrodes. The liquid level should be maintained above the bottom of barrier 7 so that hydrogen and fluorine generated

cannot mix in the gas space above the electrolyte.

For production of fluorine the cell is filled to a level slightly below operating level with an anhydrous electrolyte comprising an acid potassium fluoride of about the composition KF:1.8HF maintained in liquid condition (above 70° C.) by passing a heating fluid through jacket 2. Current is then passed through the cell to generate fluorine and hydrogen and the temperature of the cell is prevented from rising above 110° C. by passing a cooling fluid through the jacket 2. The gases bubbling through the liquid cause the electrolyte to rise to normal operating level. This level is maintained by addition of hydrogen fluoride. Product gases are withdrawn continuously for purification or for use directly.

The application of the thermo-siphon principle to the operation of electrolytic cells as described herein is not claimed as our invention but constitutes the subject of U. S. Patent Application Serial Number 558,700 filed October 14, 1944.

It will be understood that we intend to include variations and modifications of the invention and that the preceding examples are illustrations only and in no wise to be construed as limitations upon the invention, the scope of which is defined in the appended claim, wherein

We claim:

In an electrolytic cell for the generation of fluorine comprising a single vertical plate type cathode and an anode comprising a nickel plate attached to a single surface of an anode support,

said anode support comprising a substantially horizontal iron bar extending substantially completely across one face of said anode and welded to the nickel anode by substantially continuous welds along the horizontal edges of the bar near the top of the anode and on the side of the anode remote from the cathode, and a copper electrical connector comprising a vertical copper rod extending up through the top of the cell, and united to a horizontal copper bar bolted to the iron anode-supporting bar.
